UNITED STATES PATENT OFFICE.

THERON W. CHAPMAN, OF BELVIDERE, ILLINOIS.

GUARD FOR BOTTLE-CORKS.

1,158,028.

Specification of Letters Patent.

Patented Oct. 26, 1915.

Application filed September 14, 1914. Serial No. 861,644.

To all whom it may concern:

Be it known that I, THERON W. CHAPMAN, a citizen of the United States, residing at Belvidere, in the county of Boone and State of Illinois, have invented certain new and useful Improvements in Guards for Bottle-Corks, of which the following is a specification, reference being had to the accompanying drawings.

10 My invention relates to a certain new and useful guard for bottle corks and for use particularly with bottles the contents of which are deadly or dangerous.

It is well known that many mistakes frequently resulting in death, are made in improperly selecting medicine bottles particularly in the dark.

20 My invention has for its object the production of a guard to be used with bottles containing poisons or dangerous drugs such guard when used will make mistakes such as referred to impossible and with this end in view my invention consists in the details of construction hereinafter more fully set forth.

25 In order that my invention may be fully understood and its advantages appreciated I will proceed to describe the same referring by numerals to the accompanying drawing, in which—

30 Figure 1 is a side elevation of a bottle provided with one of my improved guards, Fig. 2 is a similar view at a right angle to that shown at Fig. 1, Fig. 3 is a section on the line *a—a* of Fig. 1, Fig. 4 is a perspective 35 view of the guard removed from the bottle, and Fig. 5 is a similar view of a modification of the guard.

Similar reference numerals indicate like parts in the several figures of the drawing.

40 1 represents an ordinary bottle used for containing drugs and medicines and having the usual neck 2 and flanged top 3 adapted to receive a cork 4.

45 The guard is composed of comparatively thin sheet metal and consists of a narrow band 5 one end of which is formed with a transverse slot 6, adapted to receive the other end of the band which after passing through the slot is bent over as clearly shown, to 50 secure the device to the neck of the bottle under the flange 3. The band is formed with two or more upright projections 6^x of a height about equal to the upward projection of the cork or other stopper which may be 55 used to close the bottle.

The metal of which the guard is made should be sufficiently ductile to permit of bending the projections 6^x around the flange 3 of the bottle and into the position shown at Fig. 1.

60 From the construction and arrangement shown it will readily be seen that if an attempt is made to grasp the cork 4 with the fingers the projections 6^x will guard the cork and the fingers will slip off of these projections thus the person attempting to withdraw the cork will be notified that the contents of the bottle are dangerous.

65 While I have shown at Fig. 1 the preferred form of the guard as having only two vertical projections, it may be made with more than two as shown at Fig. 5 so that the cork cannot be approached from any angle without contact with the guard.

70 I prefer to make these guard projections comparatively wide at the upper end and having a degree of elasticity as tending to more readily cause the slipping of the fingers, but variations may be made in the particulars mentioned and in other details of construction without departing from the principle of my invention which resides in providing a bottle with a removable guard adjacent to the cork which will constitute notice that the contents of the bottle are dangerous.

75 What I claim as new and desire to secure by Letters Patent is:

80 The combination with a bottle having an annular flange at the outer end of the neck, 85 of a guard for the cork within the neck comprising a band, a plurality of arms carried by the band and projecting at right angles therefrom, said arms being bent to engage the upper and lower face of the annular flange, said arms being substantially 90 circular in form at their outer ends and comparatively wide with reference to the cork, to guard the approach of fingers to the cork and to induce the slipping of the fingers, 95 substantially as hereinbefore set forth.

100 In testimony whereof I hereunto affix my signature in the presence of two witnesses.

THERON W. CHAPMAN.

Witnesses:

JOHN W. ELDREDGE,
F. W. CRAIN.
